APPARATUS FOR APPLYING PULVERIZED OR SHREDDED MATERIAL
TO THE INTERIOR OF TUBULAR ARTICLES

Filed May 1, 1922

INVENTOR
LUCIEN I. YEOMANS

By Chindahl Parker Carlson
ATTYS.

UNITED STATES PATENT OFFICE.

LUCIEN I. YEOMANS, OF CHICAGO, ILLINOIS, ASSIGNOR TO PIONEER PRODUCTION COMPANY, OF CHICAGO, ILLINOIS, A CORPORATION OF ILLINOIS.

APPARATUS FOR APPLYING PULVERIZED OR SHREDDED MATERIAL TO THE INTERIOR OF TUBULAR ARTICLES.

Application filed May 1, 1922. Serial No. 557,633.

To all whom it may concern:

Be it known that I, LUCIEN I. YEOMANS, a citizen of the United States, residing at Chicago, in the county of Cook and State of Illinois, have invented a certain new and useful Apparatus for Applying Pulverized or Shredded Material to the Interior of Tubular Articles, of which the following is a specification.

10 This invention has special, although not exclusive, reference to the production of foundry molds used in casting long tubular articles as, for example, cast-iron pipes and the like.

15 It is customary to coat the sand facing of a foundry mold with powdered anthracite coal or other suitable material, commonly called "blacking". The purpose of the blacking is to ensure a smooth clean casting surface to which the sand does not become burned and adhere. The heat from the poured metal gasifies the blacking and the gas acts as a blanket until the iron "sets".

20 When the form and dimensions of the mold permit, the blacking is applied in dry form by means of a brush. Sand molds which can be coated with dry blacking are known as "green-sand molds" and can be poured at once or as soon as the core is set.

25 30 Attempts have been made to apply a dry coating of blacking to long molds of small diameter, such as pipe molds, but such attempts have not been commercially successful. The standard practice in applying blacking to pipe molds of relatively small diameter is to mix the blacking with water and pour it down the molds, after which the mold must be dried, becoming what is known as a "dry-sand mold". The drying

35 40 operation is very expensive, requires a large amount of space and hampers the carrying out of a continuous process of molding and pouring the castings.

45 As applied to the pipe-casting industry, the purpose of the present invention is to render possible the application of blacking in dry form to the interior of molds of relatively small diameter, thus obviating the necessity of drying the mold.

50 The accompanying drawing represents diagrammatically an apparatus for applying blacking to the interior of pipe molds of small diameter.

In the drawing, A represents a pipe mold having a sand facing A'. The blacking-applying apparatus comprises means for circulating air charged with blacking through the mold until sufficient blacking adheres to the sand. The means herein shown for this purpose comprises a fan 1 55 or other means for inducing a circulation of air through a circuit comprising pipes 2, a tubular support 3 upon which the pipe mold may stand in upright position, and a cap or hood 4 adapted to fit upon the upper end of the pipe mold. Any suitable means may be employed to provide a sufficiently air-tight connection between the ends of the pipe mold and the parts 3 and 4. For example, the support 3 may have a covering 60 5 of felt on which the mold rests, and the lower side of the cap 4 may have a similar covering 6 of felt.

Any suitable provision may be made for facilitating the insertion of the pipe mold 75 into the blacking-applying apparatus and its removal therefrom. Herein the cap 4 is shown as hinged at 7 so that it may be swung upwardly out of engagement with the pipe mold to permit the withdrawal of 80 the latter and the substitution of another mold to be blacked.

At a suitable point in the circuit, means is provided for introducing blacking. Herein is shown a hopper 8 having any ordinary 85 feeding means arranged to be operated by means of a hand crank 9. The blacking discharged from the hopper 8 falls into the line of piping forming the circuit and is carried through the circuit by the air current 90 induced by the fan 1.

It is desirable, although not essential, that the fan 1 be operated continuously. In order that this may be practicable, I provide a pipe 10 arranged to communicate 95 with the circuit at points at opposite sides of the fan 1 and at opposite sides of the gap in the circuit into which the mold is inserted. The means herein shown for controlling communication between the pipe 100 10 and the main circuit includes two three-way valves 11 located at the juncture of the ends of the pipe 10 with the pipes 2. Any preferred means may be employed to operate the valves 11 simultaneously, as, for example, a sprocket chain 12 extending over

sprocket wheels 13 fixed to the oscillatory valve members of the valves 11.

In operation, the velocity of the air while passing through the mold should be slow enough to prevent any damage to the mold through carrying off particles of sand, and to allow the particles of blacking to become deposited on the sand. If the piping outside of the mold were of the same internal diameter as or larger than the mold, blacking would settle in the piping. Consequently I make the pipes 2 of smaller diameter, as herein shown, whereby the air has a greater velocity while passing through the piping and will pick up and carry the blacking instead of depositing it, and will deposit the blacking only at the lower velocity obtaining in the mold. When the proper amount of blacking has been applied to the mold, the valves 11 are operated to establish communication between the pipes 2 and the pipe 10 and to cut off the flow of air through the support 3 and the cap 4. The mold is then replaced with another, and the valves 11 operated to establish communication between the pipes 2 and the support 3 and the cap 4, and cut off communication between the pipes 2 and the pipe 10.

Inasmuch as the blacking is moved through a closed system, there is no waste of blacking.

It will be apparent that the invention herein disclosed is susceptible of use in coating the interior of tubular articles of various sorts with any desired material capable of being suspended in a current of air. The apparatus herein shown may also be employed to circulate any desired gas or mixture of gases (whether charged with powdered material or not) through a tubular article. I therefore desire that the following claims shall be construed broadly.

I claim as my invention:

1. An apparatus for applying blacking in dry form to the interior walls of a pipe mold having, in combination, a tubular support upon which the pipe mold may stand in upright position, a cap movably supported for movement into and out of engagement with the upper end of the pipe mold, a conduit connecting said support and said cap, a fan for inducing a current of air through said conduit, the cap, the pipe mold and the support, means for introducing blacking into said conduit, a pipe arranged to communicate with said conduit at points at opposite sides of said fan, and valves controlling communication between said pipe and said conduit, said conduit being of smaller internal diameter than the pipe mold.

2. An apparatus for applying blacking in dry form to the interior walls of a pipe mold having, in combination, a tubular support upon which the pipe mold may stand

in upright position, a cap movably supported for movement into and out of engagement with the upper end of the pipe mold, a conduit connecting said support and said cap, a fan for inducing a current of air through said conduit, the cap, the pipe mold and the support, and means for introducing blacking into said conduit, said conduit being of smaller internal diameter than the pipe mold. 75

3. An apparatus for applying powdered material or the like to the interior walls of a tubular article comprising a fluid-conducting circuit having a gap into which the article may be inserted to form a part of the circuit, means for inducing a flow of fluid through the circuit, a pipe connected to the circuit at opposite sides of said gap, means for controlling communication between said pipe and the circuit, and means for introducing powdered material or the like into the circuit. 80

4. An apparatus for "blackening" green-sand pipe-molds of relatively small diameter comprising means to circulate a blacking-laden air current through the mold to permit the deposition of dry blacking on the interior walls of the mold. 90

5. An apparatus for applying powdered material or the like to the interior walls of a tubular article comprising an air-conducting circuit having a gap into which the article may be inserted to form a part of the circuit, means for introducing such material into said circuit, and means for inducing a current of air in the circuit. 95

6. An apparatus for applying powdered material or the like to the interior walls of a tubular article comprising an air-conducting circuit having a gap into which the article may be inserted to form a part of the circuit, means for introducing such material into said circuit, and means for causing the air to flow in the circuit. 100

7. The combination of a system of pipes adapted to be connected to opposite ends of a tubular article, a fan to circulate air through said piping and tubular article, said piping being of smaller diameter than said article, and means for introducing coating material into the air stream for circulation through said article. 110

8. An apparatus for treating the interior walls of a tubular article comprising a gas-conducting circuit having a gap in which the article may be inserted to form a part of the circuit, means for inducing a flow of gas through the circuit, a pipe connected to the circuit at opposite sides of said gap, and means for controlling communication between said pipe and the circuit. 120

9. In a device for treating the interior walls of a tubular article, a main conduit forming a fluid conducting circuit, and an auxiliary conduit connected to the main 130

conduit to form a by-path for the fluid, said main conduit being adapted for insertion of the article to form a section thereof.

10. In a device for treating the interior walls of a tubular article, a main conduit forming a fluid conducting circuit and an auxiliary conduit connected to the main circuit to form a by-path for the fluid, said main conduit being adapted for insertion of the article to form a section thereof, and means for regulating the flow of fluid through said auxiliary conduit.

11. An apparatus for applying powdered material or the like to the interior walls of a tubular article comprising a main conduit adapted as a fluid conducting circuit, means for inducing a flow of fluid through the circuit, means for introducing powdered material or the like into the circuit and an auxiliary conduit connecting two points of the main conduit to form a by-path between said points, said main conduit being adapted for

insertion of the tubular article therein between said points.

12. An apparatus for applying powdered material or the like to the interior walls of a tubular article comprising a main conduit adapted as a fluid conducting circuit, means for inducing a flow of fluid through the circuit, means for introducing powdered material or the like into the circuit and an auxiliary conduit connecting two points of the main conduit to form a by-path between said points, said main conduit being adapted for insertion of the tubular article therein between said points to form a section of the main conduit, and means operable to selectively control the passage of fluid through the main conduit and tubular article, and said by-path respectively.

In testimony whereof, I have hereunto affixed my signature.

LUCIEN I. YEOMANS.
